UNITED STATES PATENT OFFICE

2,571,010

NURSING BOTTLE

Frank B. Busch, Toledo, Ohio, assignor to Owens-Illinois Glass Company, a corporation of Ohio

Application October 10, 1946, Serial No. 702,547

1 Claim. (Cl. 215—11)

1

The present invention relates to improvements in nursing bottles and more particularly to the nipple and cover therefor.

An object of my invention is the provision in a nursing bottle, of a rubber nipple having a vent so positioned and formed that it may be positively sealed by a special cap or closure. Thus leakage of milk or other liquid through the vent may be avoided.

Another object of my invention is the provision of a novel and efficient closure, or cap, which is so formed as to have sealing contact with the vent when attached to a nursing bottle.

A further object of my invention is the provision of a cap, or closure, for a nursing bottle, which cap embodies novel means for slightly compressing and indenting the tip end of a nipple to thereby seal the opening, or openings therein and prevent leakage.

It is also an object of my invention to provide a nursing bottle wherein the nipple is completely enclosed by a cap, or closure and the nipple and cap are so constructed and cooperate with each other in such fashion that irrespective of the various possible positions assumed by the filled bottle, the liquid cannot flow into the space between the nipple and cap, as so often occurs.

Other objects will be in part apparent and in part pointed out hereinafter.

In the accompanying drawings:

Fig. 1 is a side elevational view of a nursing bottle embodying my invention;

Fig. 2 is a top plan view thereof;

Fig. 3 is a side elevational view showing the nipple attached to the neck portion of a bottle; and

Fig. 4 is a detail sectional view showing the cap sealing the vent and openings in the tip of the nipple.

In the illustrated embodiment of my invention I have shown it associated with a glass bottle 10 which is formed with a reduced neck 11 providing a mouth 12 having closure retaining screw threads 13 and beyond the threaded area, a further constricted portion 14 surmounted by a head 15 or annular bead which presents a downwardly facing shoulder designed for holding engagement with a nipple 16, as will be explained hereinafter.

This nipple generally is of the conventional form and includes an annular base part 17 provided with an internal rib 18 adapted for engagement with the head 15, referred to above and with a reduced neck portion 19 terminating in an apertured bulb-like tip 20.

2

Venting means for the nipple consists of a small aperture 21 extending through a thickened area 22 of the nipple, near the upper margin of the base 17 and in such position that it opens into the mouth of the bottle. The entire nipple, including the venting aperture 21 is completely enclosed by means of a cap, or closure 23.

This cap, or closure 23, consists of an annular skirt, or attaching flange 24 and a diametrically reduced crown 25, rising above the skirt and connected to the latter by an annular wall 26. The crown is of slightly greater internal diameter than the external diameter of the nipple neck 19 and is formed with a sealing protuberance 27, which extends downward centrally from the closed end of said crown for the purpose of indenting the tip of the nipple and sealing the apertures temporarily. The annular wall 26 may be placed at any desired angle of inclination radially, or may be horizontally disposed. It provides a vent sealing surface which contacts and closes off the outer end of the vent 21 incident to attachment of the cap to the container, such attachment being obtained by means of interengaging screw threads 13 and 29 on the container and cap, respectively.

It will be understood that all of the usual functions of venting means, etc., of nursing bottles, are inherent in the present invention. Additionally, I have provided positive sealing means for both the apertures in the nipple neck and the vent in the shoulder portion thereof. Both of these sealing means are effective incident to screwing of the closure to the position shown in Fig. 4 wherein the projection 27 on the crown 25 closes the opening, or openings in the nipple tip, and the annular wall 26 seals the vent opening. As a consequence, it is impossible for any liquid to leak through these openings into the space between the cap and nipple, such as often occurs with the usual nursing bottle.

Modifications may be resorted to within the spirit and scope of my invention.

45 I claim:

In combination, a container having a reduced neck defining a mouth, a rubber nipple secured to said neck and including a shoulder and an attaching base part, an annular radial wall at 50 the upper margin of the base, a reduced neck rising from said shoulder, an apertured tip closing the outer end of said neck, said wall having a vent opening formed to provide communication between the interior of the container and 55 the atmosphere at times, a cap for completely

enclosing the nipple, means for attaching the cap to said container, a radial annular wall intermediate the ends of said closure for sealing the vent opening when the closure is secured to the container, and means forming a part of said cap for indenting and thereby sealing the apertured tip, said last named means including a depending projection positioned axially of said cap.
